[57] CLAIM

The ornamental design for a chandelier with five shades, as illustrated and described.

DESCRIPTION

FIG. 1 is a top perspective view of the chandelier with five shades;

FIG. 2 is a side elevational view, all sides being identical;

FIG. 3 is a top plan view of the chandelier; and,

FIG. 4 is a fragmentary view of the chandelier, two of the supporting arms and shades being omitted for enhanced disclosure of the center post and remaining shades.
